UNITED STATES PATENT OFFICE.

JACOB ISAACS, OF ALBANY, NEW YORK.

DESIGN FOR A CIGAR-HOLDER.

SPECIFICATION forming part of Design No. 25,469, dated May 12, 1896.

Application filed February 18, 1896. Serial No. 579,800. Term of patent 3½ years.

To all whom it may concern:

Be it known that I, JACOB ISAACS, a citizen of the United States, residing at Albany, in the county of Albany and State of New York, have invented and produced a new and original Design for Cigar-Holders and Ash-
receivers, of which the following is a specification, reference being had to the accompanying drawings, forming part thereof.

10 In the drawings forming part of this specification, Figure 1 is a plan view of my original design for a cigar-holder and ash-receiver. Fig. 2 is a longitudinal central vertical section on line 2 2 thereof; and Fig. 3, a transverse section on line 3 3, these figures being deemed necessary to fully illustrate my design.

15 The leading feature of my design consists in an oblong block A, the ends of which are circular in form, as shown at a, in which is fitted a circular opening or chamber B, and

in the upper side of said block, between said chambers B, is formed a longitudinal semi-circular recess C, the block being cut away or inclined at each side of said recess from the 25 top to the bottom, as shown at D.

My design is regular in form and outline and the general contour thereof produces a pleasing impression upon the eye.

Having described my design, I claim and 30 desire to secure by Letters Patent—

The design for cigar-holders, as herein shown and described.

In testimony that I claim the foregoing as my invention I have signed my name, in presence of the subscribing witnesses, this 14th day of February, 1896.

JACOB ISAACS.
